(57) **CLAIM**

The ornamental design for packaging and display box for a TV game controller, as shown and described.

DESCRIPTION

FIG. 1 is a perspective view of a packaging and display box fro a TV game controller showing my new design;

FIG. 2 is a left side view thereof;

FIG. 3 is a bottom plan view thereof;

FIG. 4 is a rear elevational view thereof; and,

FIG. 5 is a perspective view thereof with the tear strip removed.

The broken lines in FIG. 5 are for illustrative purpose only and form no part of the claimed design.
